UNITED STATES PATENT OFFICE.

WILLIAM W. WALLACE, OF FRANKFORT, INDIANA.

BRICK AND TILE MACHINE.

SPECIFICATION forming part of Letters Patent No. 288,894, dated November 20, 1883.

Application filed March 30, 1883. (No model.)

To all whom it may concern:

Be it known that I, WILLIAM W. WALLACE, of Frankfort, in the county of Clinton and State of Indiana, have invented a new and Improved Brick and Tile Machine, of which the following is a full, clear, and exact description.

My invention consists of an improved contrivance of apparatus for utilizing hydraulic and screw pressure together in the press for pressing the clay through the dies for forming the bricks, tiles, and other objects, by which stiffer clay can be worked and the products increased.

15 It also consists of an arrangement of two presses and pressing apparatus in such relation with the mixer that the operation may be continuous with reciprocating presses by alternate action; and it also consists of improvements in the apparatus for combining the hydraulic and screw presses, all as hereinafter fully described.

Reference is to be had to the accompanying drawings, forming part of this specification, 25 in which similar letters of reference indicate corresponding parts in all the figures.

Figure 1 is partly a plan view and partly a horizontal section of my improved press. Fig. 2 is a side elevation. Fig. 3 is an end elevation, and Fig. 4 is a transverse section of Fig. 1.

I arrange two pressing-cylinders, *a*, side by side horizontally, each having a spiral presser-screw, *b*, located at the end where the clay is to be pressed out through the dies *c*, and a 35 reciprocating plunger, *d*, to condense the mud and force it onto the screw. The mixer *e* is located over the pressing-cylinders, so as to discharge into both through passages *f*, and the shaft *g* of the mixer extends down through 40 the bottom of the mixer-case and between the cylinders to the space below, where it gears by bevel-wheels *h* with a horizontal shaft, *i*, extending to the housing-frame *j* at the opposite end of the machine, where it gears by the 45 wheel *l* with the wheels *m*, that turn the pressing-screws by their shafts *n*, one of which wheels *m* gears with the driving-shaft *o* by the pinion *p*. The shafts *n* extend through the plungers *d*, and also through tubular rods *q* 50 of said plungers, which extend through the hydraulic cylinders *s*, wherein they have pis-

tons *t* connected to them, and out through stuffing-boxes *u*. The hydraulic cylinders are connected by the induction-pipes *v* and three-way cock *w* with a system of hydraulic 55 pumps, *x*, and with the reservoir *y* by the induction-pipes *z* and the three-way cock *a'*. These cocks are connected by arm *b'*, lever *c'*, and connecting-rods *d'* and *e'* with a shifter consisting of weighted lever *f'* and a poising-lever, *g'*, which is operated by one of the plunger-rods *q*, by bar *i'*, and arm *p'*, said bar having pins *t'* to throw it at the proper time, so that when the plungers arrive at the end of the stroke in one direction the shifter will reverse the cocks, so that the plungers will be 65 reversed, said plungers being connected together by their rods *q* and a chain, *j'*, and pulley *k'*, so that by alternately exhausting the filled cylinder and filling the empty one the 70 continuous action of the hydraulic reciprocating plungers will be produced, the plungers being forced against the clay by the hydraulic liquid, and being forced back by each other. The pumps are geared in this case with the 75 shaft *o*, and will be arranged as such pumps commonly are. When the plunger of one pressing-cylinder is going forward, the delivery of clay to said cylinder from the mixer will cease, the other one in which the piston 80 is going back then being filled. By the use of the two forms of presses clay can be worked much stiffer and with less tempering, in which condition it is more uniform in temper, and the work may be done faster.

Having thus described my invention, what I claim as new, and desire to secure by Letters Patent, is—

1. The combination, in a machine for pressing tiles, bricks, and other articles through 90 forming-disks *c*, of a screw-presser and a hydraulic plunger, substantially as described.

2. The combination, in a brick-machine, of a pair of continuously-revolving screw-pressers and a pair of alternately-acting hydraulic 95 plungers, substantially as described.

3. The combination, in a brick-pressing machine, of a mixer, *e*, two pressing-cylinders, *a*, a pair of continuously-revolving screw-pressers, and a pair of alternately-acting hydraulic plungers, substantially as described.

4. The combination, in a brick-pressing ma-

chine, of a pair of hydraulic plungers, *d*, pressing-cylinders *a*, hydraulic cylinders *s*, and pistons *t*, reservoir *y*, pumps *x*, three-way cock *w* in the induction-pipes *v*, three-way cock *a'* in the eduction-pipe *z*, and the shifting mechanism connected with the cocks and with one of the piston-rods, substantially as described.

5. In a brick-pressing machine having a pair of reciprocating hydraulic plungers and hydraulic apparatus for working them, the said plungers connected to each other by the

rods *q*, chain *j'*, and a pulley, *k'*, for reversing the plungers by each other, substantially as described.

15 6. The shafts *n* of the screw-pressers, extended through the hydraulic plungers and their rods, and geared with the mixer-shaft and driving-shaft, substantially as described.

WILLIAM W. WALLACE.
